The ornamental design for an underwater motive device, as shown and described.

DESCRIPTION

FIG. 1 is a perspective view of an underwater motive device showing my new design;

FIG. 2 is a right side view thereof;

FIG. 3 is a left side view thereof;

FIG. 4 is a top view thereof; and

FIG. 5 is a bottom view thereof;

FIG. 6 is a front view thereof; and

FIG. 7 is a rear view thereof.

The portions of the article shown in broken lines form no part of the claimed design.
